UNITED STATES PATENT OFFICE.

ALEX A. CLARKE, OF DALLAS, TEXAS.

SURFACE-TREATING MACHINE.

1,352,583.

Specification of Letters Patent. Patented Sept. 14, 1920.

Application filed March 26, 1918, Serial No. 224,748. Renewed February 6, 1920. Serial No. 356,797.

To all whom it may concern:

Be it known that I, ALEX A. CLARKE, a citizen of the United States, residing at Dallas, in the county of Dallas and State of 5 Texas, have invented certain new and useful Improvements in Surface-Treating Machines, of which the following is a specification.

This invention relates to surface-treating 10 machines.

The idea involved in this invention is to provide a surface-treating member in an annular form and to dispose within the same a complete driving and operating unit, where- 15 by the member is revolved, and to associate with said member and unit a support whereby the surface-treating member is carried and may be applied to the work under full control of the operator.

20 In carrying out the invention an annular surface-treating or abrading member is mounted on a self-contained motor unit which in turn is mounted in a supporting frame. The motor unit is electrically driven 25 and this obviates gears and other power transmitting devices and provides for simplicity as well as a direct application of the power to the abrading member. The motor unit is journaled in the supporting frame, 30 and the said frame has on each side of the abrading member a pair of legs or standards, one of which is adjustable, whereby the support may be adjusted toward and from the work and the depth of the cut or 35 pressure of the surface-treating member controlled at will.

In a more specific embodiment of the invention a rectangular supporting frame is provided and carries at each corner a leg, 40 the legs at one end being adjustable. An electric motor is mounted in the frame and is of that type in which the fields revolve and are carried in a cylindrical housing. On the periphery of this housing an annular 45 surface-treating member is confined. The feet or outer extremities of the supporting legs are brought into contact with the surface to be treated and by the adjustment provided the projection of the surface-treat- 50 ing member beyond the plane of the extremities of said legs is controlled, and said surface-treating member may be adjusted to the work to a minute degree.

The supporting frame is provided with

suitable handles by which the workman may 55 hold and control the machine.

The invention will be more readily understood from a reading of the following specification and by reference to the accompanying drawings, in which an example of the 60 invention is illustrated, and wherein—

Figure 1 is a side elevation of a machine constructed in accordance with this invention, a portion being illustrated in section,

Fig. 2 is an end elevation of the same, and 65 Fig. 3 is a plan view.

In the drawings the numeral 1 designates a flat plate forming part of a supporting frame. At each corner of one end of the plate standards 2 project at right angles and a similar pair of standards 3 are provided at the opposite end of said plate. On each side the standard 2 is connected with the standard 3 by a side bar 4 substantially parallel with the plate 1. The standards 3 are 70 connected by a cross bar 5 in the same plane with the bars 4. The parts 1 to 5 inclusive form a supporting or carrying frame the particular formation of which may be varied. A stationary armature 6 has its ends fastened in the side bars and extends between same centrally of the frame. A motor housing 7 surrounds the armature and carries the usual fields (not shown), whereby 75 it is revolved. A commutator 8 is carried by 80 the housing and brush-terminals 9 mounted on the plate 1 have engagement with said commutator. The motor unit is not illustrated in detail as it is of a type now in common use and well known in the art of electricity. Wires 10 lead from the terminals 9 85 to a switch socket 11 adapted to receive an attachment plug 12 whereby electric current may be supplied to the motor and controlled 90 as desired.

95 The housing 7 has a broad smooth periphery and carries an annular abrading member 13 fitting snugly thereon and formed of suitable material as sand paper, emery cloth or the like. It will be seen that the surface-treating member is carried by a revolving motor unit and gears and similar driving elements are eliminated. This provides a very simple construction and affords not only a direct application of the power to the 100 surface-treating member but a high speed of revolution which is quite desirable in this 105 class of machines.

In the outer ends of the standards 2 legs 14 are fastened and on their extremities carry feet 15 of some nonabrading material so as not to scratch or mar the work when brought into contact with the same. These feet terminate in a plane which is substantially parallel to the horizontal plane of the plate 1 and substantially tangential to the member 13, so that when the feet 15 are brought into contact with the surface to be worked on, the member 13 will engage said surface as indicated in Figs. 1 and 2. Legs 16 are threaded through the standards 3 and carry feet 17 on their outer extremities. It will be readily seen that by adjusting the legs 16 the relation between the member 13 and the surface to be worked is controlled. Said legs 16 may be projected to the point where the said member 13 just engages the working surface, or they may be retracted so that the member 13 will bury itself and cut deeply into the surface being treated. It is obvious that the legs 16 should be adjusted in unison and should have their feet 17 in registration so that the member 13 will attack the working surface uniformly and evenly.

It is apparent that various means for adjusting the legs 16 might be provided. In the drawings I have shown a handle member comprising a tubular hand-grip 18 extending transversely of the plate on the opposite end from the standards 3 and rotatably confined in brackets 19. The grip 18 has portions projecting beyond the brackets and carrying beveled gears 20 which mesh with beveled pinions 21 rotatably confined in bearing boxes 22 secured to the brackets 19. The legs 16 project up through the pinions and are threaded therein so that when said pinions are revolved said legs are moved longitudinally. The legs 16 are suitably held against rotation. At the opposite end of the plate a handle member 23, having a transverse hand-grip 24 is mounted.

In using the machine the operator grasps the hand-grips 18 and 24, and after having manipulated the switch 11 to start the motor, he places the feet 15 and 17 against the surface to be treated and by turning the grip 18 the legs 16 are projected or retracted from the frame through the instrumentality of the beveled gears; thus the abrading action of the member 13 on the surface may be regulated to a nicety. If the abrading member 13 is not cutting deep enough or exerting sufficient pressure on the work the workman has only to rotate the part 18 to withdraw the legs 16, whereby the member 13 is let into the surface, but if the member 13 is cutting too deep or acting too severely on the surface the part 18 is revolved in the opposite direction whereby the legs 16 are projected and the member 13 withdrawn.

65 The pitch of the threads on the legs 16 and

the ratio of the gears and pinions are such that only a slight rotation of the part 18 is necessary to obtain an adjustment of the abrading member 13, but not so rapid as to prevent a very minute adjustment. The operator moves the machine over the surface being treated and the abrading member 13 removes the material from the surface or of the surface according to its adjustment. It is obvious that the member 13 might be a grinding member or a polishing member, but in the latter case considerable skill would be necessary on the part of the workman in passing the machine over the surface in order to get a smooth and even job, therefore the machine is more particularly designed for abrading and grinding rather than polishing.

It will be seen that the machine may be used to work on surfaces in all positions to which access may be had. In treating the surfaces of a body the top, sides, ends and bottom, both inside and outside, may be efficiently worked on, provided there is room for the machine. The machine is at all times under the direct control of the workman and owing to the high speed of revolution of the abrading member the work may be expeditiously performed.

The foregoing description and illustration clearly express the invention, but it is to be understood that said illustration is merely an exemplification and the invention may be carried out in various ways.

What I claim is:—

1. In a surface treating hand device, a supporting frame, handles on the frame whereby it may be traversed and applied to the work, a fixed horizontal armature mounted on the frame intermediate the ends thereof, a horizontal motor housing electrically energized and mounted to revolve around the armature, an annular surface treating member surrounding the housing, and projecting work sustaining elements on the frame on each side of the housing for positioning the surface treating member with relation to the surface of the work, said elements being constructed to effect an advancement or retraction of the surface treating member with relation to the surface of the work.

2. In a surface-treating machine, the combination of a supporting frame, of an electric motor mounted in the frame and including a revolving housing, an annular surface-treating member mounted on the housing of the motor, handles on the frame for holding the same, a pair of fixed legs at one end of the frame, a pair of adjustable legs at the other end of the frame, said surface-treating member being disposed intermediate the ends of the frame and between the legs thereof.

3. In a surface-treating machine, a sup-

porting frame, an electric motor mounted within the frame and having a revolving housing, an annular surface-treating member fitting on the housing, a pair of legs projecting from the frame on one side of the surface-treating machine, a pair of adjustable legs projecting from the frame on the opposite side of the surface-treating

member, a handle fixed at one end of the frame, and a combined handle and adjusting device mounted at the other end of the frame and having connections for advancing or retracting the said adjustable legs. 10

In testimony whereof I affix my signature.

ALEX A. CLARKE.
